SWITCH

Read W. Lowell, Stockton Springs, Maine

Application June 3, 1935, Serial No. 24,721

1 Claim. (Cl. 200—11)

The present invention relates to new and useful improvements in switches particularly for automobiles, but it is to be understood, of course, that a switch constructed in accordance with the present invention may be used for any purpose for which it may be adapted and desirable.

An important object of the present invention is to provide, in a manner as hereinafter set forth, a key operated main or master switch for controlling the flow of electric current from the usual storage battery of an automobile.

Another very important object of the invention is to provide a switch of the character described comprising novel means for automatically securing said switch in closed position.

Other objects of the invention are to provide a switch of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in vertical longitudinal section through a switch constructed in accordance with the present invention.

Figure 2 is a top plan view of the invention the cover of the switch casing being removed.

Figure 3 is a fragmentary view in section, taken substantially on the line 3—3 of Figure 2.

Referring now to the drawing in detail, it will be seen that the embodiment of the invention which has been illustrated comprises a casing 1 of any suitable size and material, preferably porcelain. As illustrated to advantage in Figure 1 of the drawing, the casing 1 includes a removable top or cover 2 which is secured in position through the medium of screws 3.

Journalized in the casing 1 is a shaft 4 which is actuated through the medium of a lock 5 at one end of said shaft, said lock 5 receiving a removable key 6. Fixed on the shaft 4 is a disk which is designated generally by the reference numeral 7.

The disk 7 includes a pair of connected segments 8 of current conducting material having formed therein substantially V-shaped grooves 9. Between the segments 8 are segments 10 of non-conducting material.

Mounted on the end walls of the casing 1 are substantially U-shaped resilient contacts 11 to which the conductor wires 12 are connected. The substantially U-shaped contacts 11 straddle the disk 7 on opposite sides of the shaft 4 and 5 have fixed thereon substantially V-shaped ribs 13 which are adapted to ride on the opposite faces of the disk 7 and seat in the substantially correspondingly shaped grooves 9 (see Figures 2 and 3).

It is believed that the operation of the switch will be readily apparent from a consideration of the foregoing. With the disk 7 in the position shown in Figure 1 of the drawing, the switch is closed, the current flowing from one of the contacts 11, through the connected segments 8 to the other of said contacts 11. The engagement of the ribs 13 in the grooves 9 will prevent movement of the disk 7 due to vibration or jolts, as when the automobile is in motion. To open the switch, the disk 7 is rotated to bring the non-conducting segments 10 into engagement with the contacts 11, thus disconnecting the contacts 11 electrically. Of course, rotation of the disk 7 is accomplished by inserting the key 6 in the lock 5. In addition to retaining the switch in closed position, the ribs 13, when they seat in the grooves 9, clearly indicate when the disk 7 has been rotated to the desired position for closing the switch.

It is believed that the many advantages of a switch constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

A switch of the class described comprising a casing, a shaft journaled in said casing, a disk fixed on said shaft, said disk including a pair of connected segments of current conducting material having substantially U-shaped grooves 45 therein, said disk further including a pair of segments of non-conducting material between the first-named segments, a pair of substantially U-shaped, resilient contacts mounted in the casing and straddling the disk, and substantially V-shaped ribs on the end portions of said contacts 50 slidably engaged with the opposite faces of the disk and engageable in the grooves.
